APPARATUS FOR COMMUNICATION SYSTEMS

Robert H. Brown, Westview, Pa., assignor to The Union Switch & Signal Company, Swissvale, Pa., a corporation of Pennsylvania

Application November 3, 1944, Serial No. 561,713

10 Claims. (Cl. 179—84)

My invention relates to apparatus for communication systems, and more particularly to calling apparatus for telephone systems.

In communication systems where a central office is connected to a plurality of stations through a common transmitting channel a calling means is provided. Often such calling means must be unique because the transmitting channel may be used for several different systems. For example, in railway communication a single pair of line wires may serve as a train dispatcher's telephone circuit, a telegraph circuit, and as a centralized traffic control line circuit. In each of such circuits the current used is peculiar to the use. For example, the centralized traffic control circuit may use coded direct current of the time code type and the office operator governs signaling devices at each of several stations according to the code transmitted. In such centralized traffic control systems facilities are provided for a member of a train crew or a maintainer at a station to telephone to the office operator and to initiate such telephone communication a calling means is provided. The conventional magneto ringing for a calling means is not permissible because of the nature of the other circuits using the same pair of line wires.

Accordingly a feature of my invention is the provision of improved calling means for communication systems.

Another feature of my invention is the provision of novel voice operated calling means for communication systems.

Still another feature of my invention is the provision of calling means incorporating a novel circuit arrangement to operate the calling indicator until the call is acknowledged.

Again, a feature of my invention is the provision of apparatus of the type here contemplated incorporating novel means to deionize a gas tube.

Other features, objects and advantages of my invention will appear as the specification progresses.

The above cited features, objects and advantages of my invention are attained by providing at the office a calling unit which includes a selective circuit, an electron tube, a relay, a potentiometer, a delay action means and a call bell or indicator, together with novel circuits. The office is also provided with a proper source of current. The selective circuit of the calling unit is normally connected across the line circuit and is tuned to pass the voice frequencies or to pass a preselected band of frequencies. The electron

tube is preferably of a controlled ionization type and it is provided with an anode circuit which includes the office source of power, a back contact and a winding of an office relay. Thus when the tube is fired and the associated relay is energized and picked up, the picking up of the relay opens the anode circuit and the tube is deionized. The potentiometer is connected across the current source and the control electrode of the tube is connected to an adjustable terminal of the potentiometer to provide a normal bias voltage for the tube. The parts are proportioned so that the normal anode voltage and the normal bias voltage for the tubes are insufficient to fire the tubes.

The control electrode is also connected to the selective circuit and the higher values of the voice or calling frequency current drive the control electrode in a positive direction sufficiently to fire the tube. In one form of the invention the delay action means includes a capacitor and a resistor, the capacitor being connected across the winding of the relay and the resistor being interposed in the anode circuit. When the tube is first fired the capacitor is charged at a rate predetermined by the value of the resistor. When the capacitor becomes charged current then flows in the relay winding sufficient to energize and pick up the relay. The picking up of the relay opens the anode circuit and deionizes the tube. The capacitor now discharges through the relay winding and retains the relay energized and picked up for a period. After the capacitor is discharged the relay releases to reclose the anode circuit. In this way the relay is provided both with a slow pick-up period and a slow to release period. The call bell or indicator is controlled through a front contact of the relay and is thus sounded during the slow release period of the relay. When the relay is released and the anode circuit of the tube reclosed, the tube is not again fired unless the voice frequency current is repeated. By use of a manually operable switch and overlapping contacts of the relay an alternative bias circuit is arranged for the tube and the tube once fired and the relay picked up the tube is provided with an additional bias voltage which is sufficient to fire the tube in response to the normal anode voltage. Thus this alternative arrangement provides that once the relay is picked up in response to the tube being fired due to the presence of a voice frequency current, the relay is alternately released and picked up and the call bell is intermittently operated until the call is acknowledged by the office operator taking

steps to open the anode circuit of the tube. When a relatively long delay period is required, a second relay is included in the delay action means.

I shall describe two forms of apparatus embodying my invention, and shall then point out the novel features thereof in claims.

The accompanying drawings Figs. 1 and 2 are diagrammatic views showing a first and a second form of apparatus embodying my invention when used with a railway centralized traffic control system.

In each of the two views like reference characters are used to designate similar parts.

Referring to Fig. 1, the reference characters Y and Z designate line wires which extend between two spaced locations of a railway to provide a transmitting channel between such locations. These two line wires may be used in a dispatcher's telephone circuit, a telegraph circuit and as the line circuit of a centralized traffic control system. It is to be understood, of course, that my invention is not limited to a pair of line wires used in several facilities and the line wires Y and Z may be used for telephone communication only. In order to not unduly complicate the drawings, the use of line wires Y and Z for telephone communication in connection with a centralized traffic control system only is shown. The office of such a system is indicated by a dash and dot rectangle OF and one station of the system is indicated by a dash and dot rectangle ST. Only the one station ST is shown since one station is sufficient to fully illustrate the invention.

Station ST is provided with a telephone set including a transmitter 2, and a receiver 3, which are connected in the usual manner across the line wires Y and Z through wires 4 and 5.

The office OF is provided with a calling unit indicated as a whole by a dotted rectangle CU and a battery B1 together with a telephone set comprising a transmitter 39, and a loud speaker LS and a switching key KS.

The calling unit CU includes a transformer T1, a gas tube V1, a relay LR, a potentiometer R1, a call bell CB, a delay action means comprising capacitor C2 and a resistor R2, and three switches SW1, SW2 and SW3, as essential elements.

The office battery B1 is preferably of the split battery type of a proper preselected voltage which may be for example, of the order of 110 volts. It is to be understood, of course, that other sources of direct current may be used.

The calling unit CU is provided with terminals for connection of its elements to the outside circuits and such terminals will be referred to as the apparatus is described.

The line wires Y and Z are connected through wires 6 and 7 to terminals L1 and L2 of the unit CU, and across which terminals a primary winding 8 of transformer T1 is connected through contact members 9 and 10 of switch SW2 when that switch is closed. Primary winding 8 is preferably arranged in two portions, and a capacitor C1 is interposed between the two portions. The capacitor C1 and the winding 8 are proportioned to form a circuit tuned to pass the voice frequencies or to pass a preselected band of the voice frequencies. For example, this circuit including capacitor C1 and winding 8 may be tuned to pass a voice frequency band extending from 600 to 1200 cycles per second, or it may be tuned to pass a band of only a few cycles in width.

Tube V1 may be of any one of several different types and is shown as a cold cathode gas tube having an anode 16, a cathode 17 and a control

electrode 25. Tube V1 is supplied with power from battery B1 through an anode circuit, and which anode circuit extends from positive terminal B110 of battery B1 through wire 11, terminal BP of unit CU, contact member 12 of switch SW1 when closed, transfer contact 13 and back contact 14 of a continuity transfer type of contact of relay LR, winding 15 of relay LR, resistor R2, anode 16 and tube space to cathode 17 of tube V1, wire 18, a second contact member 19 of switch SW1, terminal J1 of unit CU, wire 20, contact member 21 and contact 22 of the key switch KS, wire 23, terminal J2 of the unit CU and wire 24 to the negative terminal N110 of the battery. It is to be noted that capacitor C2 is connected in multiple with winding 15 of relay LR.

A bias voltage is applied to the tube V1 from battery B1. In this connection a mid terminal C of battery B1 is connected to terminal BL of the unit CU and the potentiometer resistor R1 is connected across the terminals BP and BL through back contact 14 and transfer contact 13 of relay LR. The control electrode 25 of tube V1 is connected to an adjustable terminal 26 of resistor R1 through secondary winding 27 of transformer T1 and resistor 28. It is to be seen, therefore, that control electrode 25 is made positive in potential with respect to cathode 17 by a voltage preselected by the position of the adjustable terminal 26. The parts are proportioned so that the voltage supplied to the control electrode is normally insufficient to cause a tube to be fired due to the voltage supplied to the anode circuit.

The call bell CB is energized by power from battery B1, the circuit for the bell including terminal B110, wire 11, terminal BP, contact member 12 of switch SW1, transfer contact 13, front contact 31 of relay LR, bell CB, and thence to the negative terminal N110 through the same connections traced for the anode circuit from cathode 17 of tube V1. Thus the bell CB is energized and sounded whenever the relay LR is picked up.

Switch SW3 governs an alternative bias circuit for the tube, and by which circuit tube V1 is provided with an additional positive bias voltage. This alternative circuit can be traced from positive terminal B110 through wire 11, terminal BP, contact member 12 of switch SW1, wire 32, switch SW3, transfer contact 33 and front contact 34 of a continuity transfer contact of relay LR and resistor 28 to control electrode 25. Since cathode 17 is connected to the negative terminal N110 of battery B1 through the connection traced hereinbefore, it follows that the control electrode 25 is provided through this alternative circuit with a positive bias voltage with respect to the cathode substantially equal to the full voltage of battery B1.

Normally, that is, when no calling voice current is applied to the transmitting channel, the tube V1 is non-conductive, relay LR is released and the call bell CB is silent. An operator at station ST wishing to call the office operator would remove the receiver 3 from the hook switch and speak an appropriate word or phrase into the transmitter 2. This word or phrase is selected to contain voice frequencies such that current flows in the selective circuit including winding 8 of transformer T1 of the calling unit CU, and a corresponding electromotive force is induced in secondary winding 27 of the transformer. The positive half cycles of such electromotive force induced in the secondary winding 27 are additive to the normal bias voltage of tube V1 and

control electrode 25 is driven in the positive direction sufficient to fire the tube. At the start of the conductive condition of tube V1, capacitor C2 charges through resistor R2, and this charge of current causes a voltage drop across resistor R2 and the voltage across the winding 15 of relay LR is relatively low at first and increases gradually as the capacitor C2 charges. When the capacitor is nearly charged and the charging current decreases to a low value, the voltage applied across the relay is sufficient to pick up the relay. The relay LR on picking up to close front contact 31 completes the circuit for the call bell and the bell is sounded as a calling signal to the office operator that the operator at station ST wishes to initiate telephone communication. When relay LR is picked up, the anode circuit is opened at back contact 14 of relay LR and the tube V1 is deionized. Capacitor C2 discharges through the relay winding 15 subsequent to the interruption of the anode circuit current and the discharge current retains the relay energized for a period. Capacitor C2 discharges in a given period and the relay is released, and with the relay released the sounding of the bell CR ceases. The reclosing of the anode circuit due to the release of relay LR fails to fire the tube unless the calling current continues or is repeated.

In response to such calling, the office operator would remove the transmitter 39 from the hook or in some other manner open the key switch KS to close contacts 35-36 and 37-38 and open contact 21-22. The closing of contacts 35-36 and 37-38 connects the office telephone set across the line wires and telephone communication can be carried on between the office and the station. The opening of contact 21-22 opens the anode circuit for the tube V1 and the calling unit is made inactive during such telephone communication.

To intermittently operate the call bell CB, the switch SW3 is closed. Under this condition a calling current applied to transformer T1 serves to fire tube V1 and pick up relay LR in the manner previously explained. When relay LR is picked up to close front contact 33-34, the alternative bias voltage is applied to the control electrode, and which alternative bias voltage is substantially the full voltage of battery B1, and is much higher than the normal bias voltage applied to the tube through the potentiometer R1. When relay LR is picked up to open the back contact the tube V1 is deionized due to the opening of its anode circuit the same as before. Relay LR is released subsequent to the discharge of the capacitor C2 and the anode circuit is reclosed at back contact 14 before the alternative bias circuit for control electrode 29 is opened at front contact 33-34 of the relay due to the continuity transfer type of contacts. The higher bias voltage is sufficient to fire the tube when the anode circuit is reclosed and thus the operation of reenergizing the relay LR is repeated and the call bell CB is again sounded. Such intermittent operation of relay LR and bell CB will be repeated over and over again until the office operator takes steps to answer the call by operating the key switch KS.

It is to be noted that if the direct current source is of the type that has no mid terminal C, the potentiometer resistor R1 would be connected between the terminals EP and J2.

Referring to Fig. 2, the line wires Y and Z extend between an office OF and a station ST to form a transmitting channel through which

telephone communication can be effected. The station ST and office OF are provided with telephone equipment which is the same as that of Fig. 1, except for the calling unit and a description of only this portion of apparatus of Fig. 2 is required.

Also in Fig. 2 the office is provided with a battery B2 of 110 volts and a battery B3 of 16 volts. It is to be understood, however, that one battery only or other source of power can be used.

The calling unit of Fig. 2 is designated as a whole by a dotted rectangle CU1. This calling unit CU1 is similar to the calling unit CU of Fig. 1, except it is provided with a second relay BR and a capacitor C3 as an additional delay action means. Also, the call bell CB is of the single stroke type and an indicator lamp LP is used to provide a continuous indication.

It is believed the apparatus of Fig. 2 will best be understood from a description of its operation.

Normally, that is, when no calling current is applied to the line wires Y and Z, the tube V1 is non-conductive, relays LR and BR are released, indicator lamp LP is dark and the bell CB is silent. Under this normal condition power is applied to the anode of tube V1 by a circuit extending from terminal B110 of battery B2 through back contact 40 of relay LR, winding 15 of that relay, resistor R2, anode 16 and tube space to cathode 17 of tube V1 and thence to terminal N110 of battery B2. Also a bias voltage is applied to control electrode 25 of tube V1 from intermediate terminal 26 of the potentiometer resistor R1 through secondary winding 27 of transformer T1 and resistor 28. The parts are proportioned for tube V1 to be normally non-conductive.

When a calling current having the preselected frequencies is applied to the line circuit, current flows in the tuned circuit including capacitor C1 and primary winding 8 of transformer T1. I have found that such calling current may be created by blowing or whistling into the microphone 2 at the station ST. In either case the calling current will have a frequency band to which the selective circuit of the calling unit can be tuned and current surges created by lightning and other conditions are of such short duration that they cause little or no response in the calling unit. The effective calling current flowing in the selective circuit induces a corresponding voltage in secondary winding 27 and the positive half cycles of such voltage drive the control electrode 25 of tube V1 in the positive direction sufficient to fire the tube. With tube V1 conducting, the capacitor C2 is charged through resistor R2 and subsequent to the charging of capacitor C2 the relay LR is energized and picked up. With relay LR picked up current flows from the positive terminal of battery B3 through normally closed contact 22 of the hook switch KS, terminal B16, front contact 41 of relay LR, back contact 42 of relay BR, a capacitor C3, resistor 43, an adjustable resistor 44, terminal N16 and to battery B3. In this form of the invention the capacitor C2 is preferably relatively small, and thus when relay LR is picked up opening back contact 40, the anode circuit of tube V1 is interrupted with the result relay LR is immediately released. With relay LR released, the anode circuit is reclosed and the tube V1 is again fired. Relay LR is thus operated as long as the calling current continues to flow. Such operation of relay LR to recurrently close front contact 41 causes capacitor C3 to receive charging pulse

each time contact 41 is closed and to discharge through the winding of relay BR each period front contact 41 is open. The parts are so proportioned that the charge supplied to capacitor C3 is greater than the discharge. The result is that capacitor C3 soon becomes charged to a voltage equal to the pick-up voltage of relay BR and that relay picks up. With relay BR picked up it is retained picked up through a stick circuit extending from terminal B16 through front contact 45 and winding of relay BR, and resistors 43 and 44 to terminal N16. During the interval relay BR is picking up current flows from terminal B16 through front contact 46, transfer contact 47 and back contact 48 of a continuity transfer contact of relay BR, bell CB and terminal N16, and the bell CB is operated for a single stroke. With relay BR picked up the lamp LP is supplied with current from terminal B16 through front contact 46 and transfer contact 47 of relay BR and lamp LP to terminal N16. Furthermore, when relay BR is picked up an alternative bias circuit for tube V1 is completed and relay LR is operated notwithstanding the calling current has terminated.

With the sounding of the bell CB and the illumination of lamp LP the office operator knows telephone communication is desired and he removes his telephone set from the hook operating the switch KS to connect the telephone set with the line circuit. The opening of contact 22 of switch KS opens the connection of battery B3 to terminal B16 and relays BR and LR of the unit CU1 are restored to their normal condition to extinguish lamp LP.

Apparatus here disclosed has the advantages that calling is effected with only the telephone set required at the station, the office apparatus is sensitive to voice current, the gas tube is powered from a direct current source, and the office call indicator can be operated once in response to the call or can be made to intermittently respond to the call until the call is acknowledged. Also the apparatus can be arranged in a single calling unit.

Although I have herein shown and described but two forms of apparatus for communication systems embodying my invention, it is understood that various changes and modifications may be made therein within the scope of the appended claims without departing from the spirit and scope of my invention.

Having thus described my invention, what I claim is:

1. In apparatus for communication between an office and a station connected by a transmitting channel, the combination comprising; an office source of current and an office calling unit; said unit including a selective circuit, a relay, an electron tube and a call indicator; said selective circuit connected to said channel and tuned to pass a preselected frequency band, said tube provided with an anode circuit to connect said current source to an anode and cathode of the tube and including a back contact and a winding of said relay, said tube also provided with a control electrode circuit to connect a control electrode and cathode of the tube to a winding coupled to said selective circuit to control the anode circuit current to pick up said relay in response to a calling current of said frequency band supplied to said channel at said station, and said call indicator governed through a front contact of said relay.

2. In apparatus for communication between a control point and a distant point connected by a transmitting channel, the combination comprising

ing, a source of current and a calling unit at said distant point; said unit including a tuned circuit, a relay, a gas tube and a call indicator; said tuned circuit connected to said channel, said gas tube provided with an anode circuit connected to said current source and including a back contact and a winding of said relay, said tube also provided with a control circuit connected to a control electrode of the tube and coupled to said tuned circuit to fire the tube in response to current of a frequency to which the tuned circuit is responsive, supplied to said channel at said control point, and said call indicator governed through a front contact of said relay.

3. In apparatus for communication between a control point and a distant point connected by a transmitting channel, the combination comprising, a source of direct current at said distant point and a calling unit having a first pair of terminals connected to said channel and a second pair of terminals connected to said current source; said unit including a selective circuit connected to said first pair of terminals and tuned to pass a selected frequency, a relay, a gas tube provided with an anode circuit and a control electrode circuit with the anode circuit including a back contact and a winding of said relay and connected to said second pair of terminals and with the control electrode circuit coupled to said selective circuit to fire the tube in response to current supplied to said channel at said control point of the frequency passed by said selective circuit, a capacitor connected across said relay winding to control the pick up and release of said relay, and a call indicator connected to a current source through a front contact of said relay.

4. In apparatus for communication between an office and a station connected by a transmitting channel, the combination comprising, an office source of direct current, an office selective circuit connected to said channel and tuned to pass a preselected band of voice frequencies, a slow action relay; a gas tube having an anode, a control electrode and a cathode; an anode circuit connected to said anode and cathode and including said current source and a back contact and a winding of said relay but ineffective to fire the tube, a resistor connected to said current source, a control electrode circuit connected to said control electrode and cathode and including a winding coupled to said selective circuit and a preselected portion of said resistor to provide a normal bias voltage of the control electrode and a control voltage to fire the tube in response to a voice current supplied to said channel at said station, and a call indicator governed through a front contact of said relay.

5. In apparatus for communication between an office and a station connected by a transmitting channel, the combination comprising, an office source of direct current, an office selective circuit connected to said channel and tuned to pass a preselected band of voice frequencies; an office gas tube having an anode, a control electrode and a cathode; an office relay having continuity transfer contacts, an anode circuit for said tube connected to said source and including a back contact and a winding of said relay to energize the relay when the tube is fired, a control electrode circuit for said tube and including a winding coupled to said selective circuit to fire the tube in response to a voice current supplied to said channel at said station, a call bell connected to said current source through a front

contact of said relay, and an alternative control electrode circuit for said tube connected to said current source and including a front contact of said relay to recurrently fire the tube subsequent to the firing of the tube by said voice current due to said continuity transfer contacts of said relay.

6. In apparatus for communication between an office and a station connected by a transmitting channel, the combination comprising, an office source of direct current, an office selective circuit connected to said channel and tuned to pass voice frequencies; an office electron tube having an anode, a cathode and a control electrode; an office slow release relay, an anode circuit to connect said current source to said anode and cathode and including a back contact and a winding of said relay, a control circuit to connect said control electrode and cathode to a winding coupled to said selective circuit to control the current flow of said anode circuit to pick up said relay in response to a calling voice current supplied to said channel at said station, a call indicator governed through a front contact of said relay to indicate such calling current during the slow release period of said relay, and an alternative control circuit connected to said control electrode and cathode through a front contact of said relay and including a bias voltage source effective to control the anode circuit current to pick up said relay, and said last mentioned front contact arranged to overlap said back contact to cause an intermittent operation of said indicator subsequent to said calling current.

7. In apparatus for communication between an office and a station each provided with a telephone set and connected by a transmitting channel; the combination comprising, an office source of direct current, an office selective circuit connected to said channel and tuned to pass voice frequencies, an office relay; an office gas tube having an anode, a cathode and a control electrode; an anode circuit to connect said current source to said anode and cathode and including a back contact and a winding of said relay, a control electrode circuit to connect said control electrode and cathode to a winding coupled to said selective circuit to fire the tube in response to a calling voice current supplied to said channel at said station, a call bell connected to said current source through a front contact of said relay to sound an indication in response to such voice current, and a key switch at said office operable to connect the office telephone set to said channel and to open said anode circuit.

8. In apparatus for communication between an office and a station connected by a transmitting channel, the combination comprising, an office power source means and an office calling unit; said unit including a selective circuit, a first and a second relay, an electron tube and a call indicator; said selective circuit connected to said transmitting channel and tuned to pass a preselected frequency band, said tube provided with an anode circuit connected to said power source

means and including a back contact and a winding of said first relay, said tube provided with a control circuit connected to a control electrode of the tube and coupled to said selective circuit to operate said first relay in response to a calling current of said preselected frequency band supplied to said channel, a capacitor connected to said power source means through a front contact of said first relay to progressively charge the capacitor in response to such operation of said first relay, said capacitor connected across a winding of said second relay to pick up said second relay when a predetermined charge is built up on the capacitor, and means including a front contact of said second relay to connect said call indicator to said power source means.

9. In apparatus for communication between an office and a station connected by a transmitting channel, the combination comprising, an office power source means and an office calling unit; said unit including a selective circuit, a first and a second relay, a gas tube and a call indicator; said selective circuit connected to said transmitting channel and tuned to pass a preselected frequency band, an anode circuit including a back contact and a winding of said first relay to connect said power source means across an anode and cathode of said tube but normally ineffective to fire the tube, a control circuit receiving energy from said selective circuit and connected to a control electrode of said tube to fire the tube in response to a calling current supplied to said channel, said first relay being recurrently picked up and released due to such calling current, a capacitor connected to said power source means through a front contact of said first relay to progressively charge the capacitor by such operation of that relay, said capacitor connected to a winding of said second relay to energize the second relay when a predetermined charge is built up on said capacitor, and means including a front contact of said second relay to connect said call indicator to said power source means.

10. In combination, a first relay, a second relay, a gas tube, an anode circuit including a back contact and a winding of said first relay to connect a power source across an anode and cathode of said tube but normally ineffective to fire the tube, a control circuit connected to a control electrode of said tube to at times apply a voltage to the tube sufficient to fire the tube, said first relay being periodically operated when such control voltage is applied, a capacitor connected to a power source through a front contact of said first relay to progressively charge the capacitor in response to such operation of said first relay, said capacitor connected to a winding of said second relay to energize said second relay when a predetermined charge is built up on said capacitor, and indicating means governed by a circuit completed through a front contact of said second relay.

ROBERT H. BROWN.
